(57) **CLAIM**

The ornamental design for implantable cardiological monitoring device, as shown and described.

DESCRIPTION

FIG. 1 is a bottom perspective view of an implantable cardiological monitoring device;

FIG. 2 is a top perspective view thereof;

FIG. 3 is a side view thereof;

FIG. 4 is another side view thereof;

FIG. 5 is an end view thereof;

FIG. 6 is another view thereof;

FIG. 7 is a bottom view thereof; and,

FIG. 8 is a top view thereof.
